METHOD OF BUILDING AND CONSTRUCTION FOR UNDERGROUND RAILROADS

Guido Janssen, Charlottenburg, Germany

Application May 13, 1931, Serial No. 537,182,
and in Germany May 13, 1930

9 Claims. (Cl. 61—42)

This invention relates to methods of and constructions for underground railroads generally known as subways.

In general, the method consists therein that 5 a provisional construction of the subway is made and thereupon provisional supporting members are removed, and after their removal, a permanent construction replaces the temporary supports, the outer shell remaining 10 throughout, first during the primary entrance of the shell into the ground and also during the various consecutive steps of the construction of the tunnel within this outer shell.

More particularly, the method consists there- 15 in that preliminarily the walls and the roof are formed by means of corrugated members which form a longitudinally arranged shaft on which the respective members are telescopically pushed forward and form thereby a shell in which 20 a provisional supporting frame is arranged. Thereafter a second protecting layer of corrugated members is provided, and thereafter a further protecting layer of corrugated members is provided. When these protecting corrugated 25 members have been inserted and properly positioned, the foundation supports, and also the construction of the normal supports with the supporting members placed thereon are provided, and the construction of the provisional 30 supporting frames takes place. Thereupon, the remaining protective layer is applied and strengthening takes place, followed by completion of the floor by filling in with building materials between and over the supporting founda- 35 tion, the building up of the walls and the stamping, spraying or pressing of the ceiling.

The construction underlying the invention consists in the exterior shell composed of corrugated members, each arranged in an inclined 40 manner, with the lowermost end of one member overlapped by the uppermost portion of the adjacent member, and having therein, first a temporary supporting construction, and upon the removal of the same, a permanent supporting 45 construction, including the base, side walls and roof or ceiling.

The object of the invention in its preferred form is to provide a very facile method of constructing underground railway tunnels, so that 50 the tunnel can be bored progressively by being forced into the earth mass and then carried on in its construction by first the provisional supporting means and finally substituted by the final construction.

55 Further objects of this invention are to pro-

vide means for constructing subways whereby the subsurface of the earth mass is telescopically bored by a metal shell and auxiliary supporting means are used within the shell to joist up the earth surrounding the same, then substituting permanent supporting means as the boring of the subsurface progresses, to provide a plurality of superposed interlocking plates inclined against the subsurface so as to form a telescopically bored opening within subsurface, 60 said plates being temporarily retained in position by the auxiliary framework, to provide a plurality of superposed corrugated plates serving as guides for movement of successive plates for driving into the subsurface of the earth 70 mass, to provide overlapping corner guides for attachment to the flanged ends of the driving plates whereby a rectangular structure is attained for driving into said subsurface, to provide an equalization device for guiding the plates 75 into the earth mass on an even plane, to provide adjustable means for lifting and bracing said auxiliary frame, to provide wedging means for securing said adjustable means whereby said latter means are retained in any desired firmly 80 set position, to provide sealing means for covering the overlapping joints of the interlocked cutting plates whereby muck or earth is prevented from escaping into the shell, and also for cementing or concreting the surface of the 85 core during the construction of the tunnel there- 90 of, to provide a method of removing material from the tunnel as the boring of the earth mass progresses and during the construction thereof, and also for transporting or supplying equip- 95 ment and building material to said tunnel.

The invention has other objects which will be clear from the specification and drawings and the invention will be further described herein- 95 after and finally pointed out in the claims.

In the drawings, Figure 1 is a longitudinal view showing the various steps in the method of construction in accordance with this invention.

Figure 2 is a section taken approximately at line 2—2 of Fig. 1.

Figure 3 is a section taken approximately at line 3—3 of Fig. 1.

Figure 4 is an enlarged partial view of the outer shell taken on the line 4—4 of Figure 2.

Figure 5 is a section taken on 5—5 of Fig- 105 ure 4.

Figure 6 is a top view looking in the direction of the arrows shown in Figure 4 on the line marked 6—6.

Figure 7 is a partial section of the roof con- 110

struction and the member supporting the same.

Figure 8 is a plan view of the supporting member in Fig. 7.

Figure 9 is an enlarged view of the part of the temporary construction shown in Figure 2 on line 9-9.

Figure 10 is an end view thereof, and

Figure 11 is a cross sectional view of a roof member used in accordance with this invention.

10 Similar reference characters indicate corresponding parts throughout the various views.

Referring to the drawings and more particularly to Figures 1 and 2, adjacent to a boring shaft in the earth mass, an auxiliary frame 1 is erected, which is shown clearly in Figure 2. Over the ceiling beam 27, and the lateral supports 3, there are pushed poling plates 4 in such a manner that they force a separation of the ground. Beneath the plates 4 further plates 4^a 20 are arranged which, by means of hydraulic devices, are forced forwardly into the ground. The guiding follows in accordance with the example shown in Figures 1, 2 and 3 by means of corrugated plates, by which the single corrugations 25 act as guides for the plates. On the outer part of the beams and the columns there are arranged equalization members or guides 5, as shown in Figures 4 and 5, which are beveled towards the outer part, so that the corrugated plates which 30 are interlocked are forced forward, and are so forced forward with an increasing inclination into the earth face to face with the flanges of the beams so as to effect a straight bore into the earth mass. The earth masses below the 35 plates 4 are then removed in any convenient manner. After the removal of about one layer of earth of about 1.5 to 2 meters, a further auxiliary supporting frame is constructed at the face of the tunnel to take care of the subsequent 40 boring into the earth mass. In case several supporting frames are erected as shown in that portion of Figure 1 indicated by A, then there is provided as is shown in part B of Figure 1, a protecting layer 6, and this is arranged on the 45 roof, on the walls and upon the floor of the shaft constructed, which protecting layer may be of any suitable material, such as concrete. Upon the hardening of this protecting layer, then in part indicated by 6 in Figure 1, a layer 7 of 50 several plies of cement or concrete flooring is arranged in the well-known manner so that flaps are left free which later serve as a good sealing means with the end layers, which serve to make the parts waterproof or water-tight. Upon this 55 protecting layer, another protecting layer 8 is placed. However, the arrangement of this sealing and the further protecting layer is only upon the floor and only partially along the walls, so that the upper part of the walls remain free 60 for the next step in the tunneling and the building operation. Upon the second protecting layer 8, there are arranged foundation joists 9 for the 65 final supporting columns, and these joists are shown in the part marked D of Figure 1. When these joists have hardened and have been firmly set on the layers 6 and 7, there follows the 70 construction of the final supporting frames, as shown in Figure 3, in which the supports 10 are placed on the lower beams or joists 9 and which 75 supports 10 are forced against the roof beams 12 and against the roof by means of hydraulic presses or jacks 11, so that an absolutely secure and tight contact is obtained, and a lowering or other movement of the earth mass is entirely prevented. The lateral supports 10^a are placed

upon a step or recess 13 of the beams 9 in such a manner that they coact on their inner sides with an abutment 14 after they have been connected with the ceiling or roof beams 12, and underwedging and a good understamping in can take place to prevent any collapse or undermining of the earth around the frame. The central supports or girders 12^a are firmly set against the ceiling by means of auxiliary members 15, while the roof of the tunnel is kept rigid by means of provisional supports 10 and hydraulic devices, which latter are properly understamped. There follows then the section indicated at D of Figure 1, in which section the roof may be sealed by means of wrought-iron plates 16 which are pressed upon the brackets 19 (Fig. 7) of the auxiliary support, whereupon the plates are secured in their position by means of block timbers 17 and wedges 18. Then follows the permanent erection of the beams 12 and the girders 12^a, whereupon after the completion of this construction, the timber 17 and wedges 18 can be removed as also the brackets 19, from the supports 3, 20, 21, 22 and 23. Then all of the auxiliary frames are removed from the completely erected final supporting frames, so that, as shown in the section F, the frames lying between the joists 9 are removed, whereupon the floor as shown in the section G of Figure 1 is stamped, whereby the longitudinal slots provided in the floor provide a good connection of the single joists. In the section H of Figure 1, the walls and the roof are completed so that in the section I of Figure 1, the completed tunnel is ready for use.

It is to be noted that, as the work of boring the earth progresses in the direction to the left of section A shown in Figure 1, cross beams 57 are laid across the floor of the tunnel. These cross beams may be of concrete or steel. Placed above the cross beams are base plates provided with proper means for retaining the supports 12^a as shown in Figure 3.

The provisional frames as shown in Figure 2 consist, as already mentioned, of several supporting columns indicated by the reference characters 3, 20, 21 on one side of the frame and 22, 23 and 3 on the other side of the frame, as shown in Fig. 2. Both of these parts are supported on hard wood beams 24 and 25 and are braced against each other by means of a set screw 26. The roof beams also consist of two parts indicated by 27 and 28 and to these the supports are bolted on as shown by 60 in Fig. 4. These braces are set in the position shown in Figure 2 to prevent any possible collapse of earth on the walls of the tunnel. In order to transfer evenly the side pressure exerted against member 3 to the base 29 and to the cap 30, there are arranged sloping struts 31 and 32 which are preferably strengthened by means of a fourth beam 33. During the building in of the provisional frames, the wooden beams are first pressed away from each other by means of a set screw 26 and thereupon the roof beams are pressed upwardly by means of jacking or hydraulic devices so that an aftersliding or falling of the earth cannot possibly take place.

The screw jacking or lifting device is indicated in Figure 10. After forcing the supports 14^a upwardly, the screw rod of the hydraulic lifting jack is secured by a safety device and is adapted so that the pressure, after the supports have taken their proper position, may be released. In order, also, that the bracing of the 150

sides may have a corresponding movement, corresponding to the raised column supports as shown in Figures 9 and 10, there is arranged on the base of the support 20 struts 32 with plates 34, as shown in Fig. 10, which are guided between two angle irons 35, as shown in Fig. 10. These angle irons have longitudinal slots whereby the fastening screws 62 can be changed in accordance with the upward pressure of the supporting frames and thereby allow for a change in position of the strut 32. After the supporting frames 20 and the struts 32 have taken their proper position, then by means of two wedges 36 and 37 the base is secured in its position to

wards the bottom so that a good bearing is obtained. The wedges 36 and 37 also oppose the stresses exerted on member 20, by being hammered firmly into the shoe in which they fit.

The hydraulic jack and the angle guide slot between the angle irons 35 are built upon a plate 38 which is fastened to the ties or beams by means of ledge screws 39.

The bracing of the two frames against each other is done by means of a cross-head beam 40 shown in Figure 2 which, after the construction of the roof supports or beams is removed from its upper position and is transferred to the small brackets 41, shown in Figure 2, so as to equalize the loading stresses exerted on the supporting columns 21 and 22.

A special problem is presented and a special solution is provided in connection with the corners of the walls in respect to the telescopically driven walls. In Figures 4 and 6, there are arranged angle irons 42 shown particularly in Fig. 4 for sealing the corners of the tunnel and which are slidably connected with the flanges 43 of the corrugated plates 4, as shown in Fig. 4. For instance, as shown in Fig. 6, the plates 40 are provided with longitudinal slots 44 in which rivets 45 (shown in Fig. 4) are guided so that a movement of the angle members 42 and the flanges 43 may take place in respect to each other, during the advancement of the corners 45 and of the corrugated plates. Under such conditions there is a certain amount of tolerance between the driving plates 4 during the process of telescopically boring the earth mass.

The concreting of the roof, as shown in Fig. 50 3 takes place in such fashion that the flanges of the roof supports are provided with suitable wooden framework, such, for instance, as are usually used for concrete structures. The concrete is then stamped in, in the intermediate space or it may be pressed in, or it may be sprayed in, depending upon the particular facilities at the disposal of the builders.

In Figs. 7 and 8 there is shown on an enlarged scale the construction of the brackets 55 19 which are used for retaining the elongated timbers 17. These timbers support the plates 16 and thereby assist in sealing the roof. The bracket 19 is provided with angle plates 46, which are joined to the angle irons 47. Both the angle plates 46 and the angle irons 47 are connected to the supporting column 20 by bolts or screws, as shown.

It is to be noted that after the roof has been concreted and the plates 16 are permanently set therein, the timber 17 and wedges 18 may be removed.

Instead of the walls being formed of corrugated plates there is preferably provided as shown in Fig. 11, a profile angle iron structure. This is substantially a U-shaped profile with

the flanges 48 bent outwardly and to these are connected lateral flanges 49. One of these flanges carries a tongue 50, and the other a groove 51 for interlocking with a structure of the same profile but of smaller size. By the interlocking of such a profile structure with others, the guiding takes place not only by means of the grooved sides 52, but also by means of projections 53 provided with a step 54 and a guiding surface 55 so that the above profiles may rest one upon another, being guided by their edges 56 passing between the step 54 and the surface 55 of the adjacent irons or profile structure.

In the middle of the roof, there are arranged supporting corrugated plates, beams, or ties with equalizing plates which slide one upon another as shown in Fig. 2.

If there is any danger of sand or the like escaping through the joints or overlaps, for instance at 44 and at 61, then in order to stop up the leaks and prevent any loss of sand or dirt, a cementing (not shown) of the joints or overlaps may be carried out, in such manner, that, for example, core material is brought to the outside by means of pipes which are conducted to the outside through the overlapping, thereby sealing the joints or lappings with the core material.

Furthermore, instead of the building out, or of the mucking out at the face of the tunnel as the telescoping process progresses, according to the method of utilizing a shield, a process for solidifying the concrete or stone may be used in which the layers or stone may be formed at 105 suitable intermediate spaces by means of sprayed or conducted hardening fluid and preferably several layers or parts of layers may be produced, one behind the other. The removal of the earth mass is done from top to bottom by 110 which procedure it is again taken care of by the pre-arrangement of further hardening layers.

For the removal and transportation of the muck and of the building material, transporting 115 machinery extending through several stories is provided or a suitable track may be utilized. One upper track may be used for the removal of muck while another lower track may be used for the transportation of material whereby the lower track is arranged at such a position that work can be done beneath it.

It is to be noted that the invention in its preferred embodiment consists in telescopically driving by hydraulic or other means corrugated 120 or interlocked superposed plates so joined by overlapping angle iron plates as to form three sides of a rectangle. The driving of the plates into the earth mass is guided by an inclined 125 equalization plate whereby the plates are driven at an even plane, thereby forming a shell whose sides are permanently concreted or cemented. While the tunneling progresses, auxiliary frames are set up in the core of the tunnel to provide auxiliary temporary bracing means which are 130 subsequently reinforced until the proper size of the core is obtained. The auxiliary bracing means are then replaced by permanent girders and cross beams. The flooring of the tunnel is 135 reinforced by cross ties or beams to effect a permanent foundation for the ceiling and wall beams whereupon the roof and sides are concreted or cemented or built in, in accordance with the foregoing description.

The tunnel in its process of construction con- 140

145

150

tains tracks laid therein for the transportation and removal of material and equipment.

I have described an embodiment of my invention and the general way of carrying out my method, but it is clear that changes may be made therein without departing from the spirit and scope of the invention as defined in the appended claims.

I claim:

10. 1. The method of constructing subways and the like, substantially as herein described, which consists in telescopically driving forwardly a plurality of superimposed poling plates to form top and side walls of a shaft, while simultaneously setting up temporary provisional supporting framework against the formed sides and top thereof to permit removal of the soil from the resultant shaft, adding a protective layer of building material around the plate walls and a base on the floor of the shaft, superimposing a plurality of columns horizontally and transversely of the shaft and on the base thereof, and as the telescoping progresses to form the shaft installing permanent columns adjacent the side walls and girders to support the top wall, filling in the plate structures the side walls and the foundation with a lining of building material, and finally removing the temporary framework.
15. 2. In the method according to claim 1, the steps in which the superimposed poling plates are telescopically driven forwardly into the soil at an incline to the longitudinal axis of the subway shaft, while installing the provisional temporary framework to support the plates constituting the top and side walls to permit further progress of said advancing of the subway shaft.
20. 3. A method of subway construction according to claim 1, in which the walls of the core or shaft of the subway are provided with a layer of concrete for hardening the surface and reinforcing the layer in one or more planes according to the respective distance of the auxiliary frame from the end of the core.
25. 4. A framework section substantially as herein described for tunnels and the like, comprising two spaced horizontal beams and one vertical beam, or horizontal beam and the vertical beam being joined end to end while the lower horizontal beam is adjustably engaged with the vertical beam, a vertical column supporting the top and bottom horizontal beams at one of their free ends, and a brace having a vertical column intermediate the vertical beam and the vertical column and parallel therewith and struts extending from the ends thereof with one arm bearing against the side beam for supporting the side and top walls of the tunnel, and screw jacking means on the vertical columns for adjusting the same in the frame and forcing said columns upwardly against the top tunnel wall.
30. 5. In a tunnel construction substantially as herein described, the combination with a plu-

rality of superimposed telescopically driven corrugated top and side wall plates, of a rectangular double-sectioned framework separated at the central portion thereof, a vertical column, bearing against the top and bottom of said framework at the central portion thereof, struts extending from the top and bottom of the frame for bearing against the sides of the framework, and screw jacking means, for adjusting the sections of the framework, the vertical column and the struts, whereby to maintain the framework rigidly against the wall plates and prevent any subsidence thereof.

6. In a tunnel construction substantially as herein described, the combination with a plurality of superimposed corrugated top and side poling plates for cutting out a subterranean shaft, overlapping slidable angle iron sheet plates joining said top and side plates and forming the corners thereof, said sheets being movable relatively of one another to permit expansion of the plates, of a foundation joist at the floor of the tunnel, a plurality of spaced vertically adjustable supports, a plurality of roof beams held by said supports and adjacent in end to end relation for supporting the top plates, lateral supports bearing against the side plates and one of the vertical supports, and a central spacer support intermediate two vertical supports for retaining the same vertically against the roof beams.

7. In a subway construction according to claim 5, a plurality of superimposed poling plates, each provided with tongues and grooves and with inclined steps, said parts serving as guides for the adjacent plates.

8. In a subway construction according to claim 5, a plurality of poling plates each provided with overlapping slidable corner angle plates so that when one plate is pushed forward with respect to the other plate, an expansion by enlargement of the corner surface can take place.

9. In a construction for tunnels, a framework comprising a plurality of rectangularly disposed frame sections for bearing against the top, bottom and side walls respectively of the tunnel, said top and bottom frame sections being in spaced apart relation at the center of the tunnel to leave free ends thereat, vertical columns adjacent each free end of the frame and disposed near the center of the tunnel and bearing against the free ends of the top and bottom walls of the tunnel, struts in connection with the braces bearing against the side sections of the framework, and jacking means on the braces extending from the bottom sections of the frame for adjusting the framework tightly against the walls of the tunnel and exerting pressure against the top, bottom, and side walls of the tunnel.
